UNITED STATES PATENT OFFICE

2,354,373

SUBCARBURETOR

Lincoln Hanks, Tacoma, Wash.

Application February 3, 1943, Serial No. 474,514

12 Claims. (Cl. 123—119)

This invention relates to devices to be applied to an internal combustion engine, and especially to means whereby the power of the engine is increased without a corresponding increase in the gasoline fuel consumed, in other words in which the ratio between the miles driven and the gasoline consumed is increased.

The objects of my invention are: first, to increase the above-mentioned ratio; second, to provide means for utilizing the water vapor from the heated radiator; third, to provide means for utilizing the heat of the exhaust gases from the engine; fourth, to provide means to bring a stream of rectified exhaust gases into the flow of fuel; fifth, to provide means for utilizing the vapor from the fuel tank; sixth, to provide means for utilizing the vapor from the oil sump of the engine; seventh, to provide means whereby the flow of these several vapors may be automatically controlled by the suction of the engine; and eighth, to provide means whereby the control of the flow of such vapors may also be controlled either by a manual connection or by connection to the foot-throttle pedal.

I attain these and other objects by the devices, mechanisms, and arrangements illustrated in the accompanying drawings, in which—

Fig. 1 is a diagrammatical view showing my improved subcarburetor connected to the main carburetor and the other essential parts of the automobile, showing the engine and its normal parts in broken lines; Fig. 2 is a vertical section of that form of my improved vapor control valve which can be controlled by either or both the suction of the engine and mechanically; Fig. 3 is a vertical section taken on the line 3—3 in Fig. 4, showing also the automatic form of my control valve; and Fig. 4 is a plan view of my apparatus, parts being broken away to reveal the interior thereof.

Similar numerals of reference refer to similar parts throughout the several views.

As clearly seen in Fig. 1, my improved apparatus is inserted between the normal carburetor and the engine. Under the conditions of very slow speed and very high speed driving, my apparatus is automatically being adapted to effect its economy of action at speeds which might be called normal, or cruising speeds, within a comparatively narrow range. This range of action may be adjusted within certain limits to suit the preference of the particular automobile operator.

Referring particularly to Fig. 1 it will be seen that the engine 5, outlined in broken lines, is

provided with the usual carburetor 6 and air cleaner 7, mounted above my improved mixing chamber 8, and with the usual heat exchange chamber 9 below the said mixing chamber 8, as well as the usual exhaust pipe 10, fuel pump 11, fuel tank 12, and water-cooling radiator 13.

Gasoline vapor from above the level of the gasoline in the tank 12 is normally allowed to escape through the vent which is necessary for the admittance of air into the tank 12 to take the place of the gasoline pumped therefrom by the fuel pump 11. However, as seen in the drawings, I increase the amount of this gasoline vapor by admitting this needed air through one or 15 more vent pipes 14 which are open to the air at their upper ends and which lead into the bottom of the tank 12. A baffle 15 is suitably supported above the orifice of each vent pipe 14, in the tank 12, in order to break up the air bubbles rising therefrom through the gasoline. The vapor thus formed is led away from the tank 12 by means of the pipe 16 to one or more of the control valves hereinafter described.

Water vapor is formed above the water in the 20 cooling radiator 13 and is led therefrom by the pipe 17 to another of the control valves hereinafter described.

A rectifier, represented by the box 18, is mounted on the heat exchange chamber 9 and is connected to the exhaust passage therein. This rectifier is adapted to change the composition of some of the exhaust gases to enrich them, whereby the rectified exhaust gases increase the combustibility of the vapors with which they are 25 mixed in the mixing chamber 8. The rectified gases are led from the rectifier 18 to the mixing chamber 8 by means of the pipe 19. Some of said rectified gases are led through the heat exchange jacket of the mixing chamber 8 and are 30 exhausted therefrom by the pipe 20 leading to the exhaust pipe 10 of the engine 5. The remainder of said rectified gases are injected into the streams of vapor as they enter the mixing chamber, as hereinafter described.

Referring now to Figs. 3 and 4, illustrating the mixing chamber structure, it will be seen that the structure is secured between the carburetor 6 and the heat exchanger 9 by means of bolts through the flanges 21. The carburetor passage 35 22 leads to the inner mixing chamber 23 and out by the passage 24. The chamber 23 is provided with a freely rotating fan 25, suitably mounted in the center thereof on a ball bearing 26, which is supported on a spider 27. The fan 25 is provided with a baffle 28 which rotates

with it and which directs the vapors from the passage 22 outward to the outer portion of the chamber 23. The fan is rotated by the flow of vapors from the passage 22 to the passage 24. The lower part of the wall 29 forming the mixing chamber 23 is provided with annular flanges 30 adapted to catch any liquid and permit it to evaporate.

The outer wall 31 of the mixing chamber structure 8 is well separated from the inner wall 29 and forms the heat exchange jacket into which the pipes 19 and 20 lead, thus supplying this jacket with hot gases whereby the chamber 23 is heated.

A plurality of vanes 32 extend into the heat exchange chamber and are adapted to direct the hot gases therein against the wall 29 as they pass around outside of the chamber 23, thereby insuring sufficient heat therein to vaporize any liquid drops therein.

In Fig. 3 is shown the simplest form of control valve for supplying vapor to the mixing chamber 23. In this case the pipe 33 carries vapor from the gas tank, or oil sump, or the radiator, to the upper end of the upper valve chamber 34, the connection being controlled by the spring-actuated valve head 35. This valve 35 is provided with a guide stem 36, having grooves 37 extending lengthwise thereof and slidably fitting in the lower cylindrical chamber 38. The pipe 39 leads from the inner mixing chamber 23 to this lower chamber 38. A spring 40 is mounted below the valve head 35 to press it upward against its seat.

When the pressure in the chamber 23 is reduced, by the suction of the engine, to a predetermined point determined by the pressure of the spring 40, the valve head 35 is moved downward against the action of the said spring, thus admitting vapor into the chamber 34. The vapor then passes down through the grooves 37 and into the mixing chamber 23. The lower that this pressure is brought to by the engine the more restricted becomes the area by which the vapor may pass in the grooves 37 of the valve stem 36, so that eventually at minimum pressure in the chamber 23 the vapor passages are entirely closed off.

Referring, now, to Fig. 2, I have illustrated another form of this vapor control valve in which the passage for the vapor may be controlled not only by the low pressure in the mixing chamber 23 but also by manual or foot control. In this case the pipe 33, carrying the vapor, enters the upper chamber 41 without restriction by any valve. The apparatus comprises two main bodies 42 and 43 joined together by an intermediate body 44. The upper body 42 forms the chamber 41. The lower body 43 is provided with a cylindrical chamber 45 which is connected to the mixing chamber 23 by the pipe 39. The intermediate body 44 is provided with a cylindrical axial passage 46 joining the two chambers 41 and 45, and the upper end 47 of this body 44 is of less diameter than the chamber 41 into which it projects. A cross-passage 48 is made in the wall of the restricted part 47, extending across it and connecting the chamber 41 with the central passage 46.

A piston 49 is slidably fitted in the lower chamber 45 and is provided with an upward-extending stem 50 slidably fitted in the passage 46 and extending above the position of the cross-passage 48. A cross-passage 51 is formed in this stem 50, said passage being adapted to register with the first cross-passage 48 when the piston 49 is

at the upper end of its stroke. An axial passage 52 leads through the piston 49 and its stem 50 to the cross-passage 51. A control stem 53 leads up from the upper end of the stem 50 and passes through the upper part 42 and is provided with an operating lever 54 adapted to turn the stem 50 and the piston 49 on their common axis. A spring 55 engages the top of the part 47 and an adjustable nut 56 on the said stem 53, thereby resisting the downward motion of the piston 49 and stem 50. An adjustable screw stop 57 passes into the lower chamber 45 to limit the downward motion of the piston 49, or it may be screwed upward to prevent any substantial movement of the said piston along its axis. A connecting rod, or other suitable mechanism, 58 connects the lever 54 with the normal throttle pedal 59 and the manual control button 60.

It is therefore apparent that the vapor, in order to pass from the chamber 41 to the chamber 45 and the pipe 39, must pass through the passages 48, 51 and 52, and it is also evident that when the piston 49 is sucked down, against the action of the spring 55, the opening between the cross-passages 48 and 51 is reduced in area. It is also apparent that the said area is further controlled by rotating the stem 50 by means of the foot pedal 59 or the manual control 60, and that this latter control is independent of the pressure-actuated control by the piston 49.

To further increase the power of the combustion of these vapors, I introduce into the several pipes 39 some of the above-mentioned rectified gases from the heat-exchange chamber between the walls 29 and 31, by means of jet fittings 61 in the said pipes 39 (Figs. 2, 3, 4).

As before stated I may take the vapors used in this apparatus either from the fuel tank 12, the oil sump of the engine 5, or the radiator 13, or from any combination thereof, depending on the circumstances thereof and the desires of the operator in the particular case.

It is, of course, understood that many changes may be made in the details of my invention as above described without departing from the spirit of my invention as outlined in the appended claims.

Having therefore described my invention, what I claim and desire to secure by Letters Patent is:

1. In an internal combustion engine having a carburetor, the combination of a subcarburetor interposed between the carburetor and the engine and containing a mixing chamber; a freely rotating fan mounted in the mixing chamber and athwart the stream of vapor passing from the carburetor to the engine, and turned thereby; a supplemental vapor supply pipe leading into said mixing chamber; and a spring-resisted automatic valve in said supply pipe and operated by the difference of pressure between the mixing chamber and the atmosphere, whereby said pipe is closed at an extreme difference of pressure and opened only at predetermined differences of pressure.

2. The combination of claim 1, wherein the mixing chamber is heated by the engine.

3. The combination of claim 1, wherein the mixing chamber is provided with means adapted to catch and retain liquid fuel; and wherein said mixing chamber is heated by the exhaust gases from the engine to evaporate said liquid fuel therein.

4. In an internal combustion engine having a carburetor, the combination of a subcarburetor interposed between the carburetor and the engine and containing a mixing chamber; a freely rotat-

ing fan mounted in the mixing chamber and athwart the stream of vapor passing from the carburetor to the engine, and turned thereby; a baffle mounted centrally above said fan and adapted to deflect the stream of vapor to the outer part of the mixing chamber; a supplemental vapor supply pipe leading into the stream of vapor in the mixing chamber; and a spring-resisted automatic valve in said supply pipe and operated by the difference of pressure between the mixing chamber and the atmosphere, whereby said pipe is closed at an extreme difference of pressure and opened only at predetermined differences of pressure.

5. In an internal combustion engine having a carburetor from which fuel vapor is sucked by the engine; the combination of a mixing chamber interposed between the carburetor and the engine; a supplemental vapor supply pipe leading into said mixing chamber; a spring-resisted automatic valve in said supply pipe and operated by the difference of pressure between the mixing chamber and the atmosphere; and mechanically operated means adapted to control the flow of vapor through said automatic valve.

6. The combination of claim 5, wherein said mechanically operated means comprises means for altering the relation between said automatic valve and the vapor passage.

7. The combination of claim 5, wherein said mechanically operated means comprises means for altering the relation between said automatic valve and the vapor passage by rotating the automatic valve therein.

8. The combination of claim 5, wherein the force of the spring applied to said automatic valve may be adjusted.

9. In an internal combustion engine having a carburetor a water-cooling radiator and a fuel tank with liquid fuel therein; the combination of a subcarburetor interposed between the carburetor and the engine, and containing a mixing chamber through which the fuel vapor passes from the carburetor; separate vapor supply pipes

leading to the mixing chamber respectively from the upper parts of the radiator and the fuel tank; and separate valve means in said vapor supply pipes and each adapted to control the flow of vapor in each such vapor supply pipe.

10. In an internal combustion engine having a carburetor, a water-cooling radiator, and an oil sump in the engine; the combination of a subcarburetor interposed between the carburetor and the engine and containing a mixing chamber through which the fuel vapor passes from the carburetor; separate vapor supply pipes leading to the mixing chamber respectively from the upper parts of the radiator and oil sump; and separate valve means in said vapor supply pipes and adapted to control the flow of vapor in each such vapor supply pipe.

11. In an internal combustion engine having a carburetor, a fuel tank with liquid fuel therein, and an oil sump in the engine; the combination of a subcarburetor interposed between the carburetor and the engine, and containing a mixing chamber through which the fuel vapor passes from the carburetor; separate vapor supply pipes leading to the mixing chamber respectively from the upper parts of the fuel tank and the oil sump; and separate valve means in said vapor supply pipes and adapted to control the flow of vapor in each such vapor supply pipe.

12. In an internal combustion engine having a carburetor, a water-cooling radiator, a fuel tank with liquid fuel therein, and an oil sump in the engine; the combination of a subcarburetor interposed between the carburetor and the engine, and containing a mixing chamber through which the fuel vapor passes from the carburetor; separate vapor supply pipes leading to the mixing chamber respectively from the upper parts of the water-cooling radiator, the fuel tank, and the oil sump; and separate valve means in said vapor supply pipes and adapted to control the flow of vapor in each such vapor supply pipe.

LINCOLN HANKS.
